UNITED STATES PATENT OFFICE.

FRANK M. PRAY, OF OAK PARK, ILLINOIS.

WALL CONSTRUCTION AND METHOD.

1,174,519.

Specification of Letters Patent.

Patented Mar. 7, 1916.

Application filed January 8, 1915. Serial No. 1,084.

To all whom it may concern:

Be it known that I, FRANK M. PRAY, a citizen of the United States, residing at Oak Park, in the county of Cook and State of Illinois, have invented a new and useful Improvement in Wall Construction and Methods, of which the following is a specification.

My invention relates particularly to wall-construction having provision for insulation against the passage of heat and impervious to the passage of moisture, and to the method of producing the improved wall.

The invention is particularly applicable to concrete wall-construction, and my primary object is to cheapen the cost of such construction and at the same time provide effective insulation against the transmission of heat and moisture.

The preferred embodiment of the invention is illustrated in the accompanying drawings, in which—

Figure 1 represents a broken elevation of a wall in process of construction, the view showing only the assembled air-envelops entering into the construction of the walls of the form; Fig. 2, a broken section taken as indicated at line 2 of Fig. 1, illustrating the condition after the form has been filled 30 in one portion with cement; Fig. 3, a transverse vertical section of the wall, in course of construction; Fig. 4, a broken plan view illustrating the manner of assembling the air-envelops employed in the wall construction; Fig. 5, a similar view showing a modification; Fig. 6, a perspective view illustrating the manner in which vertical reinforcements may be used in the construction shown in Fig. 5; Fig. 7, a broken perspective view of one of the air-envelops employed; Fig. 8, a horizontal sectional view of the same, taken as indicated at line 8 of Fig. 7; Fig. 9, a perspective view of one of the transverse re-inforcing members, which 45 serves also as a spacer for the air-envelop; and Fig. 10, a perspective view of another reinforcing clip, which serves also as a spacer.

In the preferred construction, which is 50 illustrated, A represents a foundation, or wall-fooing; B, a wall rising therefrom, and C, the removable outer form-walls. In constructing an exterior wall, for example, it is preferred to assemble between the form-walls C the air-envelops D, arranged in 55 three planes parallel with the form-walls,

as indicated at 1, 2 and 3. The air-envelops D are preferably of the construction shown in Figs. 7 and 8. That is to say, each air-envelop comprises a thin rectangular box 60 or shell 4, which may be of heavy paper, or thin cardboard; and a corrugated sheet 5 of the same material confined within the box or shell, and adapted to resist crushing and to subdivide the box itself into air-cells 5^a. 65 In a wall of approximately nine inches in thickness, each air-envelop D may be approximately one and one-quarter inches thick, one and one-half feet high, and fourteen inches in width; and, accordingly, the 70 boxes or air-envelops may be spaced approximately one and one-quarter inch apart, and approximately one and one-quarter inch from the form-walls. In the illustration given, the proportionate width of the 75 boxes is less than stated, for convenience of illustration.

The envelop 4 may be conveniently formed by bending a sheet of paper into hollow rectangular form, one edge of the 80 sheet being indicated at 6 and the other at 6^a, as shown in Fig. 7; and providing end-flaps 7 equipped with inturned flaps 8. The envelop may be secured in rectangular form by any suitable means, as by staples 9. The 85 member 5 has its corrugations running in a vertical direction, the ply of cardboard following a zigzag course from side to side of the envelop; and the lateral margins of the cardboard 5 are disposed contiguous to the 90 inner surfaces of the vertical edged walls of the envelop.

For the purpose of spacing the air-inclosing envelops and providing reinforcements in the wall, I prefer to employ a series of bottom clips E; a series of top clips E¹, and a series of lower and upper edge-clips E². These clips may be conveniently formed of wire. As shown in Fig. 9, each clip E is formed to provide vertical sockets 10, 11 and 12, the intermediate socket 11 being disposed some distance above the bottoms of the sockets 10 and 12. The outside sockets 10 and 12 are spaced from the outer form-walls by portions 13; and the intermediate 105 socket is spaced with relation to the outer socket by portions 14. Without the outer end of one of the portions 13 is connected a foot 15 which is disposed parallel with the footing of the wall, and hence perpendicular to the general direction of the transversely extending member E. The foot 15

serves to hold the clip in a vertically transverse plane, so that the sockets 10, 11 and 12 will receive the lower ends of the air-envelops D.

5 In assembling the rectangular air-envelops D, the members E are laid between the form-walls C on a footing A, as shown in Figs. 1 and 3, the outer series of envelops are arranged in the vertical plane 1, with their 10 lower ends resting in the sockets 10; the intermediate series of air-envelops are arranged in the vertical plane 2, with their lower ends resting in the sockets 11, and the inner series of air-envelops are arranged in vertical plane 3, with their lower ends resting 15 in the sockets 12. In thus arranging the envelops, the clips E², which are of general U-form, are caused to engage the lower portions of the envelops, so as to space the vertical edges of the envelops with relation to each other. Thus, the clips E² have the web or spacing portions 13^a and legs 14^a which are adapted to enter inside the vertical edge walls of the envelops, as will be readily understood 20 from Figs. 4 and 7.

The arrangement described raises the central or intermediate series of air-envelops somewhat above the two outer series of envelops, so that the joints at the upper and 30 lower ends of the envelops will be broken, or staggered. In arranging the envelops, the intermediate series are so disposed as to break joint with the flanking series, as will be understood from Fig. 2. After arranging 35 the several series of envelops on the spacers, and supporting members E, and with the lower clips E² spacing the lower ends of the envelops edgewise, the upper clips E² are inserted. The clips E¹ are 40 also applied to space the upper ends of the several series with relation to each other. Thus each clip E¹ has a vertical socket 16 adapted to slip over the upper end of the intermediate envelop, and a vertical 45 socket 17 disposed somewhat lower and adapted to slip over the upper end of an envelop of a flanking series. The sockets 16 and 17 are spaced apart by a portion 18 of the clip, and the socket 17 is spaced with 50 relation to the wall of the form by a portion 19, as shown in Fig. 10.

It will be understood that the form-walls C are made of a convenient working height, and that the height of the envelops D preferably correspond approximately with such height, and that the form-walls are built up, by sections, as the work of rearing the wall progresses, the lower sections being removed from time to time, if desired.

60 The air-envelops are assembled in the form, the concrete is poured in, thus virtually forming four parallel concrete walls 20, 21, 22 and 23, connected, as shown in Fig. 2, by vertical transverse webs 24 and 65 25, which are staggered with relation to each

other, and connected also by horizontal webs 26 and 27, which are substantially staggered with relation to each other. The arrangement is such, therefore, that the air-envelops are substantially isolated from each other, each being completely surrounded with cement wall, and, as has been explained, each air-envelop is subdivided into several air-cells by the use of the corrugated cardboard 5.

75 After one section of the wall has been completed, another form-section may be superposed over the first form-section, as shown in Fig. 3, and the operation which has been described may be repeated. This may be continued until the wall is of the desired height. If desired, one may place inside the form-walls C sheets of paper 28, which will have the effect of giving to the lateral surfaces of the concrete wall a substantially uniform porous texture. This result is obtained by the prevention of liquid cement working upward along the inside of the walls of the mold, so that a glossy or close-grained finish is avoided, and a desirable porosity of uniform character is obtained. Such a surface is well adapted to hold the subsequent coatings of plaster which are applied in finishing the wall. If desired, the outer sides of the envelops 80 one series may be coated with paraffin, or some other substance impervious to moisture, as illustrated, for instance at 29 in Fig. 3.

85 In the modification shown in Fig. 5, the envelops are designated D¹. They are assembled in the manner already described, and the same clips are employed, except that clips E³ are substituted for the clips E². The clips E³ are similar to the clips E², except that they are provided with offset vertical eyes 30 adapted to receive vertical reinforcing rods or wires 31, as shown in Fig. 6. The purpose of the modified form of clip is to facilitate the arrangement of the vertical reinforcements 31; but it will be understood that both the transverse and the vertical reinforcements used in the wall may be according to any desired arrangement.

90 The improved wall is comparatively light, strong, and serves excellently to prevent the passage of heat and moisture. The use of fibrous air-envelops, such as paper or cardboard envelops, which remain in the wall, serves the double purpose of enabling staggered air-spaces to be provided in the structure of the concrete itself, and of providing excellent non-conductors within the isolated spaces contained in the concrete structure; and, as has been pointed out, the air-envelops themselves are subdivided into separate air-cells, this being accomplished in such manner as to give to the envelops sufficient rigidity of form to prevent crushing of the envelops in the pouring operation. 95 100 105 110 115 120 125 130

The wire clips which hold the envelops in spaced relation serve excellently the function of reinforcing the concrete; and, as has been indicated, these wire clips may be supplemented by vertical reinforcements, if desired. Indeed, any suitable additional reinforcements, transverse or vertical, may be used. Of course, it is desirable to have a plurality of series of air-spaces in the wall, and to have the webs which connect the thin, vertical wall staggered, or substantially so; but any desired number of series of envelops may be employed.

It will be noted that a large saving in the use of concrete may be effected; and it will be understood that where sufficient provision is made in the wall itself against the transmission of moisture through the wall, it is unnecessary to resort to the expedient of furring, lathing and plastering the inner side of the wall. Suitable coats of plaster may be applied directly to both sides of the wall.

It will be understood that when the forms C are removed, the sheets of paper 28, where used, are stripped from the wall, leaving the wall ready for the application of coatings of plaster, when the wall is sufficiently dried.

The air-envelops and clips may be cheaply produced; and the assembling may be rapidly effected by unskilled labor.

The term "wall" is to be understood as applying to any wall, whether vertical or horizontal. The construction may be employed, in connection with suitable reinforcements, for flooring and ceiling construction, enabling flush or smooth surfaces to be obtained, while insulation against the transmission of sound, as well as against the transmission of heat and moisture, is secured.

The foregoing detailed description has been given for clearness of understanding only and no undue limitation should be understood therefrom, but the appended claims should be construed as broadly as permissible, in view of the prior art.

What I regard as new and desire to secure by Letters Patent, is:

1. A monolithic wall comprising concrete having embedded therein several parallel vertical series of air-envelops closed on all sides and spaced apart, each vertical series comprising several horizontal series arranged in superposed relation and spaced apart, the vertical joints of the several vertical series being staggered with relation to each other, and the horizontal joints of the several series being staggered with relation to each other, transverse concrete reinforcing clips initially spacing said envelops with respect to each other and with respect to the surfaces of the wall, and spacing means between the vertical edge-portions of the envelops. 50 55 60 65

2. A wall comprising a series of reinforcing clips provided with a plurality of sockets, a plurality of series of rectangular air-envelops supported in said sockets, clips connecting the upper ends of said envelops, and concrete embedding said air-envelops and clips. 70

3. A wall comprising a series of transverse clips, each clip having an elevated 75 socket and two lower sockets, three series of rectangular air-envelops supported in said sockets, and concrete embedding said air-envelops and clips therein.

4. A monolithic wall comprising concrete 80 having embedded therein several parallel vertical series of air-envelops closed on all sides and spaced apart, each vertical series comprising several horizontal series arranged in superposed relation and spaced apart, the vertical joints of the several vertical series being staggered with relation to each other, and the horizontal joints of the several series being staggered with relation to each other, and spacing means embedded 85 90 in the concrete and serving initially to maintain said air-envelops in spaced relation.

FRANK M. PRAY.
